(57) **CLAIM**

The ornamental design for a tower configuration gravimetric blender, as shown and described.

DESCRIPTION

FIG. 1 is an isometric view showing the left side, the front, and the top of the tower configuration gravimetric blender of the invention.

FIG. 2 is an elevation view of the front end of the tower configuration gravimetric blender of the invention.

FIG. 3 is an elevation view of the rear end of the tower configuration gravimetric blender of the invention.

FIG. 4 is a left side elevation of the tower configuration gravimetric blender of the invention.

FIG. 5 is a right side elevation of the tower configuration gravimetric blender of the invention.

FIG. 6 is a top view of the tower configuration gravimetric blender of the invention; and,

FIG. 7 is a bottom view of the tower configuration gravimetric blender of the invention.

1 Claim, 7 Drawing Sheets

FIG. 1
